Inventor,

James Sangster.

United States Patent Office.

JAMES SANGSTER, OF BUFFALO, NEW YORK.

Letters Patent No. 78,128, dated January 7, 1868.

IMPROVED MACHINE FOR HANDLING OR PILING BRICK.

The Schedule referred to in these Letters Patent and making part of the same.

TO ALL WHOM IT MAY CONCERN: -

Be it known that I, JAMES SANGSTER, of Buffalo, in the county of Erie, and State of New York, have invented a new and useful Device or Machine for Handling or Piling Brick or other forms; and I do hereby declare that the following specification or description is sufficiently clear and exact to enable others skilled in the art to which it appertains, or to which it is most nearly connected, to make, construct, and use the same, reference being had to the accompanying drawings, forming a part of this specification or description, in which—

Figure 1 is a plan view.

Figure 2 is a side elevation.

The nature of my invention consists in, first, the construction or arrangement of a movable partition or partitions with the frame, or that part surrounding the said movable partition; second, in the combination, with the said movable partitions, of movable handles, by means of which the said partitions may be made to move together, and clasp or hold the brick, or release it, as desired.

In said drawings, in which similar parts in the several figures are designated by similar letters, A represents the frame, B the movable partition or partitions, the ends of which are made to move in a groove or slots in said frame A, substantially as shown in fig. 2 by the letters B. G represents a spring or springs for forcing the said partition or partitions apart, so as to release the brick. I have shown spiral springs, but a flat spring may be used in their place, if desired. The letters C represent the handles. They are fastened to the frame A by the joints, as shown at H H, in fig. 2, and are arranged so as to swing upon said joints. D represents a pin or bolt or bolts. They are firmly fastened to the first movable partition or partitions at each end of the frame, and so arranged as to allow the pins or bolts D and partitions B, to which they are fastened, to be moved by the handle or handles C.

The operation of my improved device or machine for handling or piling brick or other forms is as follows: The handles C, being open in the position as shown in fig. 1 by the letter I, allow the partitions to be separated or pushed apart from each other by means of springs, or any other suitable means for accomplishing the same result, and leave the machine open, so that it may be set down over the brick as they come from the machine, either two or three at a time, or more, the number of partitions B being regulated by the number of bricks to be lifted. The handles C, being moved up into the position shown in fig. 2, force the partitions and the brick which are enclosed between them toward each other, thus holding them firmly in place, as shown in fig. 2 by the letter K. In this position they may be carried off and placed on the pile to dry, or to be otherwise disposed of.

What I claim as my invention, and desire to secure by Letters Patent, is—

1. The partitions B, when made movable by means of the handles C and pins D, substantially as and for the purposes herein described.
2. In combination with the above, I claim the springs G, so arranged as to force said partitions B apart, substantially in the manner and for the purposes herein described.

JAMES SANGSTER.
